CLAIM

The ornamental design for a refill cleaning absorbent, as shown and described.

DESCRIPTION

In a preferred embodiment the nature of this product is as an absorbent, useful in connection with a cleaning device such as a hand-held window cleaning device having a squeegee blade, for delivering and collecting cleaning fluid.

FIG. 1 is a left, top, frontal perspective view of a refill cleaning absorbent embodying our new design;

FIG. 2 is a top plan view thereof, the bottom plan view thereof being the mirror image of the top plan view shown;

FIG. 3 is a left side elevational view thereof, the right side elevational view thereof being the mirror image of the left side elevational view shown; and,

FIG. 4 is a front elevational view thereof, the rear elevational view thereof being a mirror image of the front elevational view shown.
